(57) **CLAIM**

The ornamental design for a ball-point pen, as shown and described.

DESCRIPTION

FIG. 1 is a perspective view of the front, top, and one side of a ball-point pen showing our new design;

FIG. 2 is a front elevational view thereof;

FIG. 3 is a rear elevational view thereof;

FIG. 4 is a side elevational view of an opposite side, said one said being a mirror image thereof;

FIG. 5 is a top plan view thereof;

FIG. 6 is a bottom plan view thereof;

FIG. 7 is a front elevational view thereof with the cover removed for ease of illustration, the rear and side views being identical thereto;

FIG. 8 is a top plan view thereof;

FIG. 9 is a bottom plan view thereof;

FIG. 10 is a front elevational view of the cover shown separately, removed from the pen for ease of illustration;

FIG. 11 is a rear elevational view thereof;

FIG. 12 is a side elevational view thereof, the opposite side being a mirror image thereof;

FIG. 13 is a top plan view thereof; and,

FIG. 14 is a bottom plan view thereof.
